(57) **CLAIM**

The ornamental design for an animal repeller, as shown and described.

DESCRIPTION

FIG. 1 is a front, right, and top perspective view of an animal repeller showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 6.

The dash-dash broken lines in the drawings depict portions of the animal repeller that form no part of the claimed design. The dot-dash broken lines represent boundaries of the enlarged portions shown in FIGS. 1, 6, 9, and 10 that form no part of the claimed design.
